UNITED STATES PATENT OFFICE.

JOHN C. SCHMIDT, OF CHICAGO, AND WILLIAM EICHHOLZ, OF CICERO, ILLINOIS.

DOORCHECK.

Application filed May 18, 1927. Serial No. 192,408.

1 This invention relates to certain novel improvements in door checks and has for its principal object the provision of an improved construction of this character which will be 5 highly efficient in use and economical in manufacture.

2 Among the salient objects of the invention is to provide a door check, of the character hereinafter described, which will function to 10 prevent slamming action of the door when moved into closing position either manually or by an outside agent and whereby mechanism is provided which is put into operation by the opening of the door to yieldably resist 15 the closing movement of the door without totally stopping the door in such movement.

3 A further object of the invention is to provide a door check, of the character hereinafter described, which comprises mechanism 20 for yieldably restraining without stopping the door during its opening and closing movement whereby the door will gradually close in the action of a slow steady movement without the usual chatter or vibration.

25 Other objects will appear hereinafter.

The invention consists in the novel combination and arrangement of parts to be herein- 30 after described and claimed.

The invention will be best understood by 35 reference to the accompanying drawings, showing the preferred form of construction and in which:

Fig. 1 is a transverse vertical sectional detail view of the invention;

35 Fig. 2 is a detail view taken substantially on line 2-2 of Fig. 1;

Fig. 3 is a perspective view of certain of the braking elements embodied in the invention;

40 Fig. 4 is a perspective view of an operating arm or bell crank embodied in the invention; and

Fig. 5 is a diagrammatical plan view showing the invention associated with a door and a 45 door casing.

Referring more particularly to the drawings, showing the preferred form of construction, a housing is indicated at 10. This housing has formed as an integral part thereof brackets 11 which are adapted to be attached to a door 12 through the medium of suitable connecting elements 13. The housing 10 has its open top closed through the medium of a cap plate 13 secured to the housing 10 through the medium of screws 14.

This cap plate has a centrally located boss 15 formed thereon and formed in this boss 15 is a central bore 16 for reasons hereinafter set forth. The housing 10 has formed therein a centrally located bore 17 and the lower end 60 portion, termed for convenience, the base 18, is enlarged and has a hollow interior 19. The bore 17 opens excentrically with respect to the interior 19 of the base 18 for reasons hereinafter set forth. The base 18 is closed 65 through the medium of a suitable cap 20 secured to the base by means of screws 21.

Rotatably arranged in the bore 17 is a cylinder 22. This cylinder 22 at its lower end portion is open and provided with an enlarged flange 23 which engages the interior wall of the bore 17. Formed as an integral part of the cylinder 22 is a stud 24. This stud 24 has a cylindrical portion 25 which works in the bore 16 and fitted to the outer 70 end portion 26 of the stud is an arm 27. This arm 27 has an opening 28 formed therein with one side of the opening provided with a flat surface 29 adapted to engage a flat surface 30 formed on this outer end portion 29 whereby 75 to prevent rotation of the arm 27 independently of rotation of the stud 24. The arm 27 is held from displacement from the stud 24 through the medium of a nut 31 threaded upon a threaded portion 32 of the stud and 80 against a lock washer 33. Formed in the stud 24 is a passage 34 and arranged at a predetermined point in this passage is a reduced portion 35 having a threaded opening 36 formed therein. The lower end portion of the passage 34 is restricted to provide a seat 37 adapted 85 for engagement with the tapered end portion 38 of the needle 39. This needle 39 has an intermediate portion 40 threaded for 90 threaded engagement with the threaded opening 36 and the exterior portion of the needle provides a finger cap 41 whereby to facilitate 95 adjusting the needle relative to the seat 37.

Embracing the cylinder 22 and arranged in the housing 10 is a coil spring 42. When the various parts are disposed as shown in Fig. 1 this spring 42 is under tension, this being brought about in a manner to be set forth hereinafter. One end portion 43 of this coil spring is connected to the plate 13 as at 105 44 in any approved manner. The opposite end portion 45 of the spring 42 is connected to the flange 23 of the cylinder 22 in any approved manner.

Movable in the cylinder 22 is a piston 46. 110

This piston 46 has a passage 47 formed therein and this passage has its interior portion 48 enlarged and provides a seat 49 for a pellet 50 arranged in the enlarged portion 48 of the passage.

Associated with the piston 46 is a packing structure 51 of any approved construction whereby to prevent the escape of air between the cylindrical wall of the piston and the 10 interior wall of the cylinder 22. The piston 46 has connected thereto a bolt 52. This bolt 52 has a threaded end portion 53 and threaded upon this threaded end portion is a nut 54 set in a counter sunk portion 55 of 15 the piston 46. The opposite or exterior end portion of the bolt 52 provides a slotted head 56. Pivotally connected to this slotted head through the medium of a pin 57 is one end portion of a link 58. The opposite end portion 20 of the link 58 is connected, by means of a pin 59, to a slotted end portion 60 of a bell crank 61.

The flange 23 of the cylinder 22 has formed as an integral part thereof spaced ears 62 25 and carried by these ears 62 is a pin 63 which provides pivotal connection between the ears and the bell crank 61 which in the present instance is disposed between these ears 62.

Opposite the ears 62 the flange 23 has 30 formed as an integral part thereof spaced ears 64 and slidably arranged between the ears 62 and ears 64 is a push bar 65. This push bar 65 is substantially U-shaped to provide a longitudinal slot 66. At the end portion 67 of the push bar 65 there is formed slots 68 which extend diagonally in a transverse direction with respect to these end portions and operable in these slots are end portions 69 of a pin 70. This pin 70 provides 35 connection between the arm 71 of the bell crank 61 and the push bar 65. The push bar 65 has formed at its right portion 72 a transverse ear 73 provided with a vertical opening 74. This ear 73 is adapted to be projected into the slotted head 75 formed as an integral part of a brake shoe 76. This head 75 has aligned openings 77 formed therein and these openings are adapted to register with the openings 74 and projected in these 50 openings is a pin 78 which provides pivotal connection between the push bar 65 and the brake shoe 76.

The brake shoe 76 in the present instance is substantially arcuate in plan view and has 55 secured thereto in any approved manner a suitable brake lining 79 adapted for wiping engagement with respect to the interior wall of the base 18.

The push bar 65 is slidably connected to the 60 ears 64 through the medium of screws 80 carrying washers 81 which engage the push bar along its longitudinal peripheral edges.

Formed in the end portions 67 of the push bar 65 are bores 82 and projected in these 65 bores 82 against the action of spring members

83, arranged in these bores, are pins 84 carried by a plate 85 having formed as an integral part thereof a head 86. This head 86 has a beveled surface 87 adapted for wiping engagement with the interior wall of the 70 base 18.

The arm 27 has its outer end portion 88 pivotally connected as at 89 to a link 90 pivotally connected to a bracket 91 secured to the door casing 92 with which the door 12 is 75 associated.

In operation, when the door 12 is moved to open position with respect to its casing the cylinder 22 will be rotated by action of the arm 27. In rotation of this cylinder 22 the 80 spring 42 is placed under tension. When the cylinder 22 rotates the ears 62 and 64 act to rotate the push bar and its brake shoe. As herein indicated the bore of the cylinder 22 opens eccentrically with respect to the bore 85 19 of the base 18 and when the cylinder 22 is rotated the brake shoe will have wiping engagement with the wall of the bore 19 and as rotated the brake shoe will act upon the push bar to move the same in a longitudinal direction. As this push bar moves in this longitudinal direction the bell crank 61 is pivoted about its pin 63 and pivots the end portion 60 thereof in an upward direction. This 90 pivotal movement of the bell crank in this direction will act upon the link 58 and push the piston 46 inwardly to exhaust the air from the cylinder 22. At this point it will be noted that the spring 42 is under tension, the piston 46 in its outer position with respect to the 100 cylinder 22, and the brake shoe in a position furthest from the central axis of the cylinder 22 or the bore thereof. When the door is released for movement into closing position the spring 42 being under tension tends 105 to urge the door in this movement. Co-acting against the spring 42 in its operation to urge the door into closing position is the piston 46 and brake shoe 76. As the door is urged into closing position by the spring 42 the 110 brake shoe having wiping engagement with respect to the interior wall of the bore 19 will check this closing movement sufficient to permit the door to close at a slow steady pace. As the door is moved to closing position by the action of the spring 42, the brake shoe 46 acts upon the push bar 65 and urges this push bar to move in a longitudinal direction against the springs 83. This movement of the push bar 65 will pivot the bell crank 115 61 in an opposite direction to that herein mentioned and as the bell crank pivots in this direction the link 58 will be caused to act on the piston 46 and force this piston inwardly against the atmospheric pressure within the cylinder 22. The gradual movement of the piston 46 in the cylinder 22 forces the air out through the passage 34 and by reason of the slow escape of the air through this passage 34 the piston will co-act with the brake shoe 120

125

130

to check the movement of the door sufficiently enough to permit the door to close at a slow even pace.

As the piston 46 is moved outwardly from the cylinder 22 air enters the cylinder 22 through the passage 47, it being pointed out that as the air passes through this passage 47 into the cylinder 22 the pellet 50 will be raised by the air pressure from closing position.

The needle 39 may be adjusted to regulate the amount of air to escape from the cylinder 22 when the piston 46 is moved inwardly against the air in the cylinder.

It will be manifest, from the description herein set forth, that we provide a door check which will function efficiently to control the speed of movement of a door into door closing position and that the device may be used on any type or weight of door.

It will be important to note that as the bell crank 61 pivots in either of those directions the pin 70 will work along the edges of the slots 68 and thereby prevent chattering or vibration of the push bar during either of those two movements.

While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims.

Having thus described our invention what we claim as new and desire to protect by Letters Patent is:

40. 1. A door check including a housing having a bore formed therein and comprising a base provided with a hollow interior, said bore eccentrically opening into the interior of said base, a cylinder rotatably arranged in the bore, a spring member embracing the cylinder and having one end portion connected thereto and an opposite end portion connected to the housing, means for imparting opening movement of a door to said cylinder, a piston movable in the cylinder, a brake shoe rotatably arranged in the interior of said base and having wiping engagement with respect to the interior wall of the base, a push bar having connection with said brake shoe, and means operable by movement of said cylinder for moving the piston in one direction in the cylinder for urging said push bar to actuate said brake shoe for braking engagement with respect to said base.
45. 2. A door check including a housing having a bore formed therein and comprising a base provided with a hollow interior, said bore eccentrically opening into the interior of said base, a cylinder rotatably arranged in the bore, a spring member embracing the cylinder and having one end portion connected thereto and an opposite end portion connected to the housing, means for imparting opening movement of a door to said cylinder, a piston movable in the cylinder, a brake shoe rotatably arranged in the interior of said base and having wiping engagement with respect to the interior wall of the base, a push bar having connection with said brake shoe, and means operable by movement of said cylinder for moving the piston in one direction in the cylinder for urging said push bar to actuate said brake shoe for braking engagement with respect to said base.
50. 3. A door check including a housing having a central bore formed therein, a base formed on the housing and having a hollow interior arranged concentrically with respect to the bore, a cylinder rotatably arranged in the bore and having a stud extending exterior of the housing, said stud being provided with a passage to permit exit of air from within the cylinder, a valve structure controlling passage of air through said passage, means operable by the cylinder for resisting rotation of the cylinder in one direction, a piston operable in the cylinder, a brake shoe operable on the interior wall of the base, a push bar rotatable with the cylinder and having connection with the brake shoe, a head bearing member having engagement with said wall and having slideable and yieldable connection with the push bar, said push bar having an end portion provided with slots arranged diagonally and transversely with respect to the sides thereof, a bell crank pivotally supported by the cylinder, a pin projecting through said slots and providing connection between one end portion of the bell crank and the push bar, a head bearing member carried by the piston, and a link connection between said last mentioned member and the opposite end portion of said bell crank.
55. 4. A door check including a housing having a central bore formed therein, a base formed on the housing and having a hollow interior arranged concentrically with respect to the bore, a cylinder rotatably arranged in the bore and having a stud extending exterior of the housing, said stud being provided with a passage to permit exit of air from within the cylinder, a valve structure controlling passage of air through said passage, a coil spring embracing the cylinder and having one end portion connected thereto and an opposite end portion connected to the housing for resisting rotation of said cylinder in one direction, a piston operable in the cylinder, a brake shoe operable on the interior

inder and having one end portion connected thereto and an opposite end portion connected to the housing, means for imparting opening movement of a door to said cylinder, a piston movable in the cylinder, a brake shoe rotatably arranged in the interior of said base and having wiping engagement with respect to the interior wall of the base, a push bar having connection with said brake shoe, and means operable by movement of said cylinder for moving the piston in one direction in the cylinder for urging said push bar to actuate said brake shoe for braking engagement with respect to said base, said means including a bell crank pivotally supported by said cylinder, a slot and pin connection between one end portion of the bell crank and said push bar, and a link connection between the opposite end portion of the bell crank and the piston.

5. A door check including a housing having a central bore formed therein, a base formed on the housing and having a hollow interior arranged concentrically with respect to the bore, a cylinder rotatably arranged in the bore and having a stud extending exterior of the housing, said stud being provided with a passage to permit exit of air from within the cylinder, a valve structure controlling passage of air through said passage, means operable by the cylinder for resisting rotation of the cylinder in one direction, a piston operable in the cylinder, a brake shoe operable on the interior wall of the base, a push bar rotatable with the cylinder and having connection with the brake shoe, a head bearing member having engagement with said wall and having slideable and yieldable connection with the push bar, said push bar having an end portion provided with slots arranged diagonally and transversely with respect to the sides thereof, a bell crank pivotally supported by the cylinder, a pin projecting through said slots and providing connection between one end portion of the bell crank and the push bar, a head bearing member carried by the piston, and a link connection between said last mentioned member and the opposite end portion of said bell crank.

6. A door check including a housing having a central bore formed therein, a base formed on the housing and having a hollow interior arranged concentrically with respect to the bore, a cylinder rotatably arranged in the bore and having a stud extending exterior of the housing, said stud being provided with a passage to permit exit of air from within the cylinder, a valve structure controlling passage of air through said passage, a coil spring embracing the cylinder and having one end portion connected thereto and an opposite end portion connected to the housing for resisting rotation of said cylinder in one direction, a piston operable in the cylinder, a brake shoe operable on the interior

wall of the base, a push bar rotatable with the cylinder and having connection with the brake shoe, a head bearing member having engagement with said wall and having slideable and yieldable connection with the push bar, said push bar having an end portion provided with slots arranged diagonally and transversely with respect to the sides thereof, a bell crank pivotally supported by the cylinder, a pin projecting through said slots

and providing connection between one end portion of the bell crank and the push bar, a head bearing member carried by the piston, and a link connection between said last mentioned member and the opposite end portion 15 of said bell crank.

In testimony whereof we affix our signatures.

JOHN C. SCHMIDT.
WILLIAM EICHHOLZ.
